SHOE CONSTRUCTION

Jules Q. Strong, Clayton, Mo., assignor of fifty-five per cent to C. W. Mathieson, Sedalia, Mo., and fifteen per cent to P. H. Lamphere, Denver, Colo.

Application November 27, 1944, Serial No. 565,223

6 Claims. (Cl. 36—16)

This invention relates to shoes and more particularly to a shoe having a closed heel.

One of the objects of the invention is to produce an improved stitch-down type of shoe having a closed heel.

Another object is to produce a closed heel platform shoe in which the forepart of the platform is exposed and the heel part is covered by the upper.

A further object is to provide an improved method of embodying a platform in a closed heel shoe.

Still another object is to produce an improved shoe construction which will result in a durable, neat and attractive shoe capable of being economically manufactured.

Other objects of the invention will become apparent from the following description taken in connection with the accompanying drawing showing a shoe having the invention embodied therein.

In the drawing:

Figure 1 is a side view of a shoe constructed in accordance with the invention;

Figure 2 is a longitudinal section view through the shoe with heel ready to be attached;

Figure 3 is a sectional view showing the heel attached;

Figure 4 is a sectional view taken on the lines 4—4 of Figure 2 showing the platform and the manner of attaching the forepart of the upper and the outsole thereto;

Figure 5 is a cross sectional view through the heel, said view being taken on the line 5—5 of Figure 2;

Figure 6 is a view showing the shape of the platform; and,

Figure 7 is a side view of the heel and of the upper prior to attaching to the heel end of the platform.

Referring to the drawing in detail the shoe shown as embodying the invention comprises essentially an upper 1, a platform 2, an outsole 3 and a heel 4.

The platform may be of any type of construction, but as shown it consists of a resilient member 5 surrounded by shoulder means 6. The resilient member extends over the forepart of the platform only and the shoulder means has an integral extension 7 forming the heel part of the platform. The resilient member may consist of a sheet of rubber, cork, felt, or combinations thereof, or any material giving the cushioning function desired for the forepart of the foot. The shoulder means and the heel part should be

of material which has a relatively firm and non-resilient body, but yet not too flexible, suitable material being leather, pressed paper, cardboard, prepared material commonly used for insoles or like material. Overlying the resilient member, the shoulder means and the heel part is a covering sheet 8 which is secured as by cement to the mentioned parts. This sheet may be of fabric or like material and is employed to bind the 10 resilient member and the shoulder means together. On top of the sheet 8 is a second top covering sheet 9 which is secured to the sheet 8 as by cement. This sheet 9, however, when the platform is being constructed, is secured to only 15 the forepart of the platform as indicated in Figure 2. The heel part of the platform, rearwardly of where the breast line of the heel is to occur, is formed to be narrower than the forwardly extending part of the platform, this narrow part being clearly indicated in Figure 6. If desired the sheet 8 can be eliminated.

The upper 1 of the shoe may be constructed in any manner desired and is provided with a forward part 10 and a closed heel part 11 which 20 may or may not have the usual counter. When the upper has been properly constructed as a separate unit from the platform it is attached to the platform in a special manner. The lower marginal portion 12 of the forward part 10 of 25 the upper is turned outwardly in overlying relation to the marginal portion of the forward part of the platform, thus engaging the top covering sheet 9. When in this position the marginal portion 12 is stitched to the platform as best indicated in Figure 4, the stitching 13 passing through the marginal portion 12, the top covering sheet 9, the sheet 8, if employed, and the shoulder means 6. Since the shoulder means is of a material which is firm and relatively non-resilient 30 a durable connection will be made. The upper 10 is stitched to the platform only as far back as a point corresponding to the heel breast line, that is, to the point where the narrower heel part 40 of the platform begins.

45 The heel part 11 of the upper has a lower marginal portion 14 which extends beyond the marginal portion 12, as best shown in Figure 7. This marginal portion 14 receives the heel part of the platform and is turned under its edge and then 50 secured, as by cement, to the bottom of the platform, that is, the bottom of the heel part 7. This turned under construction of the marginal portion 14 is clearly illustrated in Figures 2, 3 and 5. With the lower marginal portion 14 of 55 the heel part of the upper extending under the

edge of the narrower heel part of the platform, a smooth joint will be made at the point where the stitching of the forward part of the upper begins.

The shoe is now ready for attaching the outsole 3 and the heel 4. The heel may be of any known construction and is shown as having a wood heel member 15 covered with suitable material 16 such as leather or fabric and provided with the usual wear lift 17. The heel is attached by any suitable attaching means, which in the present instance is shown as nails 18. These nails are driven through the covering sheet 8 and the heel part 7 of the platform into the wood heel member 15. The nails do not extend through the top covering sheet 9. During nailing the heel part or tab of the top covering sheet 9 is pulled forward, as indicated in Figure 2. After the heel is attached, this heel part or tab of the sheet 9 is positioned over the heads of the nails and secured to the top sheet 8, thereby covering up the nail heads and giving the inside of the shoe a neat appearance. The sheet 9 will thus serve as the sock lining of the shoe and be one continuous piece.

The outsole 3 extends from the breast of the heel forwardly. This outsole may be attached in any well known manner and is shown as being cemented to the bottom of the platform. It may, if desired, be attached by the same stitching 13 which is employed to stitch the upper to the platform. Although the sole 3 is shown as extending forwardly from the breast line, it may be made to extend beneath the heel and the platform if such is desired. Prior to attaching the heel and outsole, a shank stiffener member 19 may be suitably attached to the bottom of the platform as indicated in Figures 2, 3 and 5.

From the foregoing description it is seen that there is provided a closed heel shoe which is neat in appearance and at the same time has a platform so embodied in the shoe that only the forward part of the platform is visible. The construction also permits the forward part of the upper to be attached to the platform by what is known as a "stitched-down" construction and the heel part of the upper attached to the platform so as to totally cover up the heel part of the platform and thereby make an attractive heel and which blends into the forepart of the shoe. No special sock lining is required as the top covering sheet for the platform also serves as this member.

Being aware of the possibility of modification in the particular shoe shown and described without departing from the fundamental principles of my invention, I do not desire that the invention be limited except in accordance with the appended claims.

What is claimed is:

1. In a shoe construction, a platform assembly having a top covering sheet extending completely across the platform at least forwardly of the heel part, an upper provided with a closed heel part, the lower marginal portion of said upper forwardly of the heel part being turned outwardly in overlying relation to the top covering sheet of the platform and secured to the platform and the lower marginal portion of the heel part of said upper receiving the heel part of the platform and being turned under and secured to the bottom side of said heel part of the platform, and an outsole and a heel secured to the bottom of the platform.

2. In a shoe construction, a platform assembly having a top covering sheet extending completely

across the platform at least forwardly of the heel part, an upper provided with a closed heel part, the lower marginal portion of said upper forwardly of the heel part being turned outwardly in overlying relation to the top covering sheet of the platform and secured to the platform and the lower marginal portion of the heel part of said upper extending beyond the edge of the heel part of the platform and being turned under and secured to the bottom side of said heel part of the platform, an outsole secured to the bottom of the forward part of the platform, a heel, and means for securing the heel to the bottom side of the heel part of the platform and in covering relation to the turned over marginal portion of the heel part of the upper, said securing means extending through the portion of the platform beneath the covering sheet and said covering sheet being secured to the heel part of the platform to cover the securing means.

3. In a shoe construction, a platform assembly comprising a resilient member, surrounding shoulder means of relatively firm and non-resilient material and a top covering sheet extending across the platform, an upper provided with a closed heel part, the lower marginal portion of said upper forwardly of the heel part being turned outwardly in overlying relation to the top covering sheet and secured to the shoulder means, and the lower marginal portion of the heel part of the upper receiving the heel part of the platform and being turned under and secured to the bottom side of said heel part of the platform, and an outsole and a heel secured to the bottom of the platform.

4. In a shoe construction, a platform construction comprising a resilient member for the forepart of the foot, relatively firm and non-resilient material providing shoulder means surrounding the resilient member and also providing the heel resting part of the platform, and a top covering sheet of non-stretchable material overlying the resilient member, the shoulder means and the heel resting part, said platform having its heel part rearward of the breast line formed narrower than the part forwardly thereof, an upper provided with a closed heel part, the lower marginal portion of said upper forwardly of its heel part being turned outwardly in overlying relation to the top covering sheet of the platform and secured to the platform, and the lower marginal portion of the heel part of the upper receiving the narrower heel part of the platform and being turned under its edge and secured to the bottom thereof, and an outsole and a heel secured to the bottom of the platform.

5. In a shoe construction, a platform assembly having a top covering sheet extending completely across the platform forwardly of the heel part, said platform having its heel part rearward of the breast line formed narrower than the part forwardly thereof, an upper having a closed heel part, the lower marginal portion of said upper forwardly of the heel part being turned outwardly in overlying relation to the top covering sheet, stitching extending through the platform, including its covering sheet, and the turned outwardly marginal portion, the lower marginal portion of the heel part of the upper receiving the narrower heel part of the platform and being turned under its edge and secured to the bottom thereof, and an outsole and a heel secured to the bottom of the platform.

6. In a shoe construction, a platform assembly having a top covering sheet extending completely

across the platform forwardly of the heel part, said platform having its heel part rearward of the breast line formed narrower than the part forwardly thereof, an upper having a closed heel part, the lower marginal portion of said upper forwardly of the heel part being turned outwardly in overlying relation to the top covering sheet, stitching extending through the platform, including its covering sheet, and the turned outwardly marginal portion, the lower marginal portion of the heel part of the upper receiving the

5 narrower heel part of the platform and being turned under its edge and secured to the bottom thereof, a heel, securing means for attaching the heel to the bottom of the heel part of the platform and extending through the portion of platform beneath the covering sheet so as to be covered by said sheet, and an outsole secured to the platform and extending forwardly from the breast of the heel.

JULES Q. STRONG.
